UNITED STATES PATENT OFFICE.

ROBERT E. L. MAXEY, OF NEW YORK, N. Y.

TIE AND FASTENING.

Application filed November 27, 1926. Serial No. 151,096.

This invention aims to provide a railroad tie of novel form, having novel means for supporting a rail, and provided with novel means for retaining the rail without resort to 5 spikes.

It is within the province of the disclosure to improve generally and to enhance the utility of devices of that type to which the invention appertains.

10 With the above and other objects in view which will appear as the description proceeds, the invention resides in the combination and arrangement of parts and in the details of construction hereinafter described 15 and claimed, it being understood that changes in the precise embodiment of the invention herein disclosed, may be made within the scope of what is claimed, without departing from the spirit of the invention.

20 In the drawings:

Figure 1 shows in top plan, a device constructed in accordance with the invention, parts being broken away;

Figure 2 is a section on the line 2—2 of 25 Figure 1;

Figure 3 is a section on the line 3—3 of Figure 1;

Figure 4 is a plan showing a modified form of the invention;

30 Figure 5 is a section taken on the line 5—5 of Figure 4;

Figure 6 is a section on the line 6—6 of Figure 4.

Referring to Figures 1, 2 and 3, there is 35 shown a metal railroad tie 1 of inverted T-shape, and including a base 2 and a rib 3 upstanding from the base. Side members 4, in the form of plates, are located parallel to the rib 3 and are attached to the rib in

40 any desired way, for instance by fastening devices 5, such as rivets. The side members 4 are located on opposite sides of the rib. The side members 4 are provided at their upper edges with tables 6 which form seats for the base flange 25 of the railroad rail.

45 The tables 6 are located approximately parallel to the base 2 and extend outwardly in opposite directions from the rib 3. The tables 6 are provided with depending lugs 9 located on opposite sides of the rib 3, the

50 tables being supplied with an abutment means 8, of hook-shape, the abutment means overhanging the tables and being disposed between the lugs 9. The abutment means, above alluded to, is located partly on one side of the rib 3 and partly on the other side

thereof, as shown in Figure 1. The side members or plates 4 are thickened, as at 7, so that, for the sake of strength, the abutment hooks 8 may be considerably wider 60 than the plates 4, as shown in Figure 3. Tightening devices are provided and include stems 10 adjustable slidably in the lugs 9, the tightening devices including hook-shaped heads 11 cooperating with the abutment means 8 to engage the base flange 25 of the railroad rail. The abutment means 8 is located between the tightening devices, nuts 12 being threaded on the stems 10.

70 The base flange 25 of the rail is placed on the tables 6, and the stems 10 of the tightening devices are inserted through the lugs 9, the heads 11 overhanging and engaging the base flange of the rail, and the nuts 12 being tightened up against the lugs 9 so that the 75 heads 11 of the tightening devices may cooperate with the abutment means 8 to hold the rail in a way which will be clear when Figures 1 and 2 are compared.

Referring to Figures 4, 5 and 6, there is 80 shown a metal railroad tie 14 of inverted T-shape, and including a base 15 and a rib 16 upstanding from the base. Side members 17, in the form of plates, are located at 85 right angles to the rib 16 and are attached to the rib in any desired way, for instance, by being formed integrally therewith. Each side member 17 has a base 18 connected at its inner end to the base 15 of the tie 14. The side members 17 are located on opposite 90 sides of the rib 16. The side members 17 are provided at their upper edges with tables 19 which form seats for the base flange 26 of the railroad rail. The tables 19 are joined at their inner ends to the rib 16. 95 The tables 19 are located approximately parallel to the base 18 and extend outwardly in opposite directions from the rib 16. The tables 19 are provided with depending lugs 21 located on opposite sides of the rib 16, 100 the tables being supplied with an abutment means 20, of hook-shape, the abutment means overhanging the tables and being disposed between the lugs 21. The abutment means, above alluded to, is located partly on one side of the rib 16 and partly on the other side thereof, as shown in Figure 4. Tightening devices are provided and include stems 22 adjustable slidably in the lugs 21, 105 the tightening devices including hook-shaped heads 23 cooperating with the abutment means 20 to engage the base flange 26 of the 110

railroad rail. The abutment means 20 is located between the tightening devices, nuts 24 being threaded on the stems 22.

The base flange 26 of the rail is placed on the tables 19, and the stems 22 of the tightening devices are inserted through the lugs 21, the heads 23 overhanging and engaging the base flange of the rail, and the nuts 24 being tightened up against the lugs 21 so that the heads 23 of the tightening devices may cooperate with the abutment means 20 to hold the rail in a way which will be clear when Figures 5 and 4 are compared.

What is claimed is:—

- 15 1. In a device of the class described, a railroad tie of inverted T-shape and including a base and a rib upstanding from the base, side members attached to the rib and located on opposite sides thereof, the side members being provided at their upper edges with tables located approximately parallel to the base and extending outwardly in opposite directions from the rib, the tables being provided with depending lugs located on 25 opposite sides of the rib, the tables being supplied with an abutment means disposed between the lugs and located partly on one side of the rib and partly on the other side thereof, and tightening devices adjustable in 30 the lugs and including heads cooperating with the abutment means to engage the base flange of a rail, the abutment means being located between the tightening devices.
- 35 2. In a device of the class described, a railroad tie of inverted T-shape and including a base and a rib upstanding from the base, tables located approximately parallel to the base and extending outwardly in opposite directions from the rib, the tables being provided with depending lugs located on oppo-

site sides of the rib, the tables being supplied with an abutment means disposed between the lugs and located partly on one side of the rib and partly on the other side thereof, and tightening devices adjustable in the lugs 45 and including heads cooperating with the abutment means to engage the base flange of a rail, the abutment means being located in oppositely-acting relation to the tightening devices. 50

3. In a device of the class described, a railroad tie of inverted T-shape and including a base and a rib upstanding from the base, side members attached to the rib and located on opposite sides thereof, the side members 55 being provided at their upper edges with tables located approximately parallel to the base and extended outwardly in opposite directions from the rib, the tables being supplied with an abutment means disposed partly on one side of the rib and partly on the other side thereof, tightening devices including heads cooperating with the abutment means to engage the base flange of a rail, and means for supporting the tightening devices in working position. 60

4. In a device of the class described, a railroad tie of inverted T-shape and including a base and a rib upstanding from the base, tables located approximately parallel to the 70 base and extended outwardly in opposite directions from the rib, the tables being supplied at one edge with an abutment means, tightening devices located at the opposite edge of the table and cooperating with the 75 abutment means, and means for supporting the tightening devices in working position.

In testimony that I claim the foregoing as my own, I have hereto affixed my signature.

ROBERT E. L. MAXEY.
